COMBINED CIGARETTE LIGHTER AND HOLDER

Solomon A. Love, Atlanta, Ga.

Application August 10, 1948, Serial No. 148,037

Term of patent 7 years

(Cl. D48—27)

To all whom it may concern:

Be it known that I, Solomon A. Love, a citizen of the United States of America and a resident of the city of Atlanta, Fulton County, State of Georgia, have invented a new, original, and ornamental Design for a Combined Cigarette Lighter and Holder of which the following is a specification, reference being had to the accompanying drawing, forming a part thereof.

In the drawing,

Fig. 2 is a top plan view thereof.

Fig. 3 is a bottom plan view.

Fig. 4 is a vertical axial section on line 4—4, Fig. 2.

I claim:
The ornamental design for a combined cigarette lighter and holder, substantially as shown.
SOLOMON A. LOVE.
